United States Patent Office

Des. 192,872
Patented May 22, 1962

192,872

SERVING TRAY

Nell Fulton, 390 S. Hauser, Los Angeles, Calif.

Filed July 28, 1961, Ser. No. 66,113

Term of patent 14 years

(Cl. D44—10)

FIG. 1.

FIG. 2.

FIG. 3.

FIG. 4.

I claim:

The ornamental design for a serving tray, as shown and described.
